UNITED STATES PATENT OFFICE

2,478,164

METHOD OFrecovering ACID IN THE
PRODUCTION OF CYCLONITE

George F. Wright, Toronto, Ontario, and Carl A. Winkler, Montreal, Quebec, Canada, assignors to The Honorary Advisory Council for Scientific and Industrial Research, Ottawa, Ontario, Canada, a corporation of the Dominion of Canada

Application December 30, 1944, Serial No. 570,812

10 Claims. (Cl. 260—541)

1.

The present invention relates to acid recovery and more particularly to the recovery of acetic acid from spent reaction liquors resulting from the manufacture of certain explosives, especially cyclonite.

In the manufacture of cyclonite, either by the process described in Bachman application, Ser. No. 495,078, filed July 16, 1943, or by the related process described in Schiessler and Ross application, Ser. No. 444,254, filed May 23, 1942, now Patent No. 2,434,230, January 6, 1948, there is produced as a by-product a spent reaction liquor containing a considerable quantity of acetic acid which may amount to as much as approximately 3.5 lbs. of acetic acid per pound of cyclonite produced in the process. The recovery of acetic acid from such spent reaction liquors is therefore essential if these processes are to be commercially attractive. However, recovery operations with such spent reaction liquors are hazardous, firstly because ammonium nitrate containing organic matter constitutes a high explosive and secondly because the liquors contain residual amounts of cyclonite which is known to be an explosive of great power and brisance.

The object of the present invention is to provide a new, improved and safe process for the recovery of acetic acid from crude acid containing ammonium nitrate and residual explosive nitramines.

A further object is to provide a method of the character described which destroys the hazardous components of spent reaction liquors resulting from the manufacture of cyclonite produced by processes involving the use of acetic anhydride and ammonium nitrate.

Another object is an acetic acid recovery process applicable to crude acetic acid containing ammonium nitrate and cyclonite, which prevents the accumulation of explosive at any point in the system or the retention of the explosive in the recovered acid.

Still another object is to provide a process that enables the recovery of acetic acid without the addition of a reagent which would remain in the recovered acid to the detriment of acid quality.

A further object is the provision of an acid recovery process which may be carried out continuously in apparatus constructed with a minimum of strategic materials, producing recovered acetic acid of over 99% purity.

Other objects and advantages of the process will be apparent as the invention is hereinafter more fully described.

In accordance with the present invention, it has

2.

been found that the acetic acid present in spent mother liquors of the type characterized above may be recovered by first fuming off the crude acid in the presence of a small amount of sulfuric acid and thereafter distilling the fumed off reaction liquor at a temperature sufficiently high to destroy any organic explosive material contained therein. By the foregoing process it is possible to recover acetic acid of over 99.5% purity. Explosive hazards are minimized during the recovery operation by the destruction of the ammonium nitrate during the fume-off step, and of the cyclonite and related compounds during the distillation step.

15 In carrying out the process of the present invention it is desirable firstly to control the fume-off and secondly to effect rapid and complete destruction of the organic explosive remaining in the fumed off liquors, without the use of a reagent which would remain in the recovered acid to the detriment of acid quality. The present invention attains these objects by means which will hereinafter be described.

20 In order more clearly to describe the invention 25 the process will be discussed with reference to the several figures of the drawing wherein:

Fig. 1 is a schematic illustration of a plant for the continuous recovery of acetic acid from spent anhydride process cyclonite reaction liquors;

30 Fig. 2 is a graphical representation of the rate of destruction of cyclonite in fumed off mother liquor-sulfuric acid mixtures at the boiling point of the mixture; and

Fig. 3 is a graphical representation of the composition boiling point data for acetic acid-sulfuric acid solutions.

35 As a matter of convenience, the invention will hereinafter be described by considering the steps of the process in the order in which they are carried out.

I. THE FUME-OFF STEP

In the manufacture of cyclonite by the Bachmann process, hexamine (preferably dissolved in 45 glacial acetic acid), nitric acid, ammonium nitrate and acetic anhydride are brought together in a reaction vessel at a temperature above about 35° C. In the manufacture of cyclonite by the Schiessler and Ross process, paraformaldehyde is 50 treated with ammonium nitrate and acetic anhydride at a temperature above about 35° C. The reaction mixture resulting from either of these processes is a slurry consisting of what may conveniently be termed "anhydride cyclonite" suspended in a mother liquor which contains among

other things, ammonium nitrate and acetic acid. For purposes of convenience, the mother liquor from both of these processes may be designated as "anhydride cyclonite" mother liquors or reaction liquors.

The process of the present invention is based in part upon the discovery that, if the undiluted filtrate or mother liquors from the above processes are heated in the presence of a small amount of sulfuric acid to a threshold temperature of about 95 to about 100° C., a violent reaction ensues during which the color of the liquid suddenly changes from straw color to deep brown and large volumes of nitrogen oxide gases are evolved. During this fume-off reaction, the ammonium nitrate together with a substantial portion of the nitric acid and the unstable nitramine by-products of cyclonite are decomposed. The violence of the reaction is due to the gas evolution which causes considerable foam. The foam however is unstable and disappears rapidly as soon as gas evolution ceases. The fume-off reaction is exothermic and the temperature of the reaction mixture rises to about 106° C. in the absence of added heat.

(a) Sulfuric acid concentration during fume-off

The fume-off reaction is self-sustaining provided sufficient sulfuric acid is present in the mixture. The sulfuric acid concentration necessary to obtain a self-sustaining fume-off depends in part upon the composition of the filtrate or of the liquor. Usually, however, the minimum amount of sulfuric acid varies from about 5% to about 10% by weight of the fume-off mixture.

(b) Nitric acid concentration during fume-off

If the anhydride cyclonite mother liquor or filtrate contains an appreciable amount of nitric acid and ammonium nitrate, the fume-off is much more violent in operation. It is therefore sometimes desirable to reduce the nitric acid and ammonium nitrate content of the filtrate prior to carrying out the fume-off reaction. This may be conveniently effected in accordance with a further aspect of the present invention by treating the filtrate with a sufficient amount of anhydrous ammonia to convert practically all of the nitric acid to ammonium nitrate which is sparingly soluble in cold (25-30° C.) neutralized mother liquor but fairly soluble in the mother liquor containing appreciable amounts of nitric acid. When the resulting ammonia-treated filtrate is fumed off very little nitrogen dioxide is formed but considerable nitrous oxide gas is evolved at a steady rate at a temperature of about 106° C.

In this connection it may be mentioned that if all the nitric acid is neutralized with anhydrous ammonia some difficulty may be experienced occasionally in sustaining the fume-off reaction. To avoid this difficulty it is preferable to neutralize the major proportion but not quite all of the nitric acid, leaving less than 1% of the nitric acid, for example, 0.5% unneutralized. Ammonium nitrate is only sparingly soluble in mother liquors containing this small amount of nitric acid and the mixture fumes off smoothly and continuously at about 106° C.

Either before or after the treatment with anhydrous ammonia, but in any event prior to the fume off, any large quantities of solid cyclonite present in the reaction mixture are of course removed by filtration. The ammonium nitrate may be readily removed from the separated cyclonite by passing hot water through the filter cake. In order to accelerate the rate at which the ammo-

nium nitrate is leached from the filter cake it is preferable to blow live steam therethrough.

(c) Temperature during fume-off

Temperature is an important factor in controlling the violence of the fume-off reaction. If the temperature is high enough to initiate rapid fume-off (about 95 to about 100° C.) the heat of the reaction is sufficient to raise the liquid temperature to about 106° C. This temperature can be maintained without further outside heat provided fresh mother liquor-sulfuric acid mixture is added at an appropriate rate. If outside heat is supplied during fume-off until the temperature of the liquid rises to 112° C., the evolution of nitrogen dioxide may cease for reasons at present unknown and the evolution may or may not be restored by lowering the liquid temperature to the proper range between about 95° C. and about 106° C. However, once the fume-off reaction has ceased due to overheating, the restoration of the fume-off is sometimes very difficult to bring about. It is therefore important to control the temperature of the fume-off reaction so that it takes place below about 112° C., and preferably so that it takes place in the neighborhood of 106° C.

Inasmuch as the constant addition of fresh mother liquor-sulfuric acid mixture assists in maintaining the fume-off at an easily controlled constant rate, continuous operation during fume-off is preferred although batch fume-off may be carried out where desired. However, in batch fume-off of even a small volume of mother liquor the reaction is sometimes quite violent and for this additional reason continuous fume-off is much to be preferred.

A convenient method of carrying out the fume-off is to start with a small volume of mother liquor maintained at fume-off temperature in a suitable reaction vessel and then to add sulfuric acid or oleum to the mother liquor until fume-off begins to take place. Thereafter additional mother liquor containing from about 5% to about 10% by weight sulfuric acid may be constantly added to the reaction vessel, the feed being pre-heated at a temperature (about 50° C.) sufficient to maintain the fume-off reaction mixture at a temperature in the neighborhood of 106° C. By providing the reaction vessel with a draw-off tap, the fumed off liquor may be withdrawn from the reaction vessel at a rate sufficient to maintain a fairly constant level in the reactor.

(d) Impurities in the fumed off liquor

The composition of the fumed off mother liquor depends of course upon the composition of the original mother liquor. The ammonium nitrate and hydrolyzable organic impurities, such as N-acetylpolymethylene - nitramines, are removed during the fume-off but approximately the original amounts of residual cyclonite and homocyclonite remain in the fumed-off mother liquor as were originally present in the mother liquor prior to the fume-off reaction. Traces of nitric acid may also be present in the fumed-off mother liquor, together with larger amounts of sulfuric acid and water. Generally, the water content will be considerably higher in the fumed-off mother liquor than in the original mother liquor; the average increase in water content being about 1.6% regardless of the original water content of the mother liquor prior to fume-off. Apparently the water formed during fume-off results almost en-

the cyclonite and homocyclonite is also produced entirely from some dehydration reaction involving ammonium nitrate and nitric acid.

II. DISTILLATION OF THE FUMED OFF MOTHER LIQUOR

(a) Destruction of cyclonite and homocyclonite

As pointed out above, the fume-off reaction does not destroy the residual cyclonite and homocyclonite contained in the mother liquor. In accordance with a further aspect of the present invention it has been found that this residual cyclonite and homocyclonite may be completely destroyed during distillation of the acetic acid, provided the fumed-off mother liquor is distilled from a sulfuric acid-acetic acid mixture containing a relatively high percentage of sulfuric acid, maintained at a temperature within the range of about 125 to about 150° C.

The rate of destruction of cyclonite in mixtures of acetic acid and sulfuric acid is dependent partly upon the temperature of the mixture and partly upon the sulfuric acid concentration. Fig. 2 is a graphical representation of the rate of destruction of cyclonite in fumed-off mother liquor-sulfuric acid mixtures at the boiling point of the mixtures. From this graph it will be apparent that 100% of the cyclonite may be destroyed in less than 2 minutes provided the sulfuric acid content of the boiling mixture is above about 20% by weight. Fig. 3 is a graphical representation of the composition-boiling point data for acetic acid-sulfuric acid mixtures and by reference to this graph it will be apparent that the boiling point of mixtures containing above about 20% sulfuric acid by volume will be above about 130° C. Accordingly in effecting the distillation of the acetic acid in accordance with the present invention, complete and rapid destruction of the residual cyclonite and homocyclonite is insured by introducing the fumed-off mother liquor into a mixture of sulfuric acid and acetic acid of at least 20% by weight sulfuric acid strength maintained at a temperature above about 120° to 140° C. In order to ensure very rapid and complete destruction of the residual organic explosive, the fumed-off mother liquor is distilled through a mixture consisting of about 40% sulfuric acid and 60% glacial acetic acid. Furthermore, inasmuch as the fume-off reaction is preferably carried out continuously it is desirable to effect the distillation in an apparatus adapted for continuous operation.

(b) Composition of the distillate

The distillate produced in accordance with the present invention consists of acetic acid of above 95% purity, the precise composition of the distillate being dependent partly upon the sulfuric acid concentration of the residue maintained in the still during distillation. The distillate contains a varying but usually very small amount of water which is derived from three possible sources, namely (1) the water in the fumed-off mother liquor resulting from the decomposition of ammonium nitrate; (2) the water produced in the distillation step by the decomposition of organic explosive material; and (3) water produced in the distillation step by the decomposition of acetic acid. The amount of water arising from the first source may be reduced to a minimum by the above described treatment of the undiluted mother liquor with anhydrous ammonia which removes most of the nitric acid and therefore greatly reduces the solubility of the ammonium nitrate in the mother liquor. The water pro-

duced by the second source is practically inalterable in quantity. The water produced from the third source varies with the sulfuric acid concentration of the still residues. Until the residue in the still attains a composition of about 14.2% sulfuric acid, 2.6% water and 83.2% acetic acid, it appears that sulfuric acid exercises no appreciable dehydrating action on the acetic acid. From about 15 to about 35% sulfuric acid content the dehydrating efficiency of the sulfuric acid increases to a maximum giving a distillate of progressively higher acetic acid strength. After a maximal dehydrating efficiency at about 35% sulfuric acid in the still residue, the efficiency decreases sharply. Accordingly the highest quality acetic acid distillate is obtained at a maximum dehydrating concentration of about 35% sulfuric acid in the still mixture. However, the total recovery of acetic acid is not maximal under these conditions and it is therefore necessary to balance purity of distillate against total recovery in selecting the most satisfactory operation conditions. Concentrations varying from about 15% to about 40% sulfuric acid in the still residues represent convenient operative ranges.

As an illustration of the composition of the distillate obtainable in accordance with the process of the present invention, an experiment was carried out with 7 l. of fumed off mother liquor containing about 5.4% sulfuric acid. This fumed off mother liquor was distilled through 130 cc. of a mixture consisting of 40% sulfuric acid and 60% glacial acetic acid using a reflux ratio of 0:1. The distillate consisted of acetic acid of over 99% purity. In some instances very small amounts of aldehydes may be present. Where it is desired to reduce the aldehyde content of the recovered acid, the acid may be digested with a small amount of aniline and then distilled. This practice, however, is usually not necessary.

III. ILLUSTRATIVE EXAMPLE

In order to disclose the nature of the present invention still more clearly a typical example will hereinafter be described with reference to Fig. I of the drawing. It should be clearly understood that this is done solely by way of illustration and is not intended to delineate the invention in its broadest aspects.

In this example it will be assumed that the cyclonite was produced in accordance with the Bachmann process by reacting hexamine dissolved in acetic acid with ammonium nitrate and nitric acid in the presence of acetic anhydride at a temperature of about 35° to about 85° C. After the reactants are brought together in the reaction vessel, the resulting slurry is withdrawn from the reactor and cooled to about 25 to about 30° C. This undiluted but cooled slurry from the Bachmann process is then treated with nearly stoichiometric amounts of anhydrous ammonia in an amount sufficient to reduce the nitric acid content to about 0.5%, thereby reducing the solubility of the ammonium nitrate in the reaction liquor.

After this ammonia pretreatment, the slurry is filtered, the cyclonite and other solid materials remaining in the filter bed being worked up by hot water wash and by passing live steam through the filter bed, prior to the purification procedure described in the above identified Bachmann application.

After the removal of the solid cyclonite the filtrate is then ready for the recovery process.

which may conveniently be carried out in the apparatus diagrammatically illustrated in Fig. 1. The apparatus as shown includes a fume-off chamber 10 (preferably constructed of Duriron) a series of boiling tubes 11, an entrainment separator 12 and an acetic acid condenser 13.

In starting the unit in operation the crude acid (i.e., the mother liquor from which the cyclonite has been filtered), together with sulfuric acid, is introduced into the fume-off chamber 10 through the charge lines 20 and 21, the proportions being so adjusted that the resulting mixture contains from about 5% to about 10% sulfuric acid, the higher concentration being generally more satisfactory in starting up the continuous system. A sufficient amount of this mixture is introduced through the charge lines to fill the hydraulic legs 22 and 23 and partially fill the pot 10. The mixture in the hydraulic leg 22 is then heated by passing steam through the steam jacket 24. After fumes begin to evolve in the fume-off pot 10 the crude acid and sulfuric acid (preferably pre-heated to about 50° C.) are constantly fed through the charge lines 20 and 21 in a ratio of roughly 95 parts by weight of crude acid to 5 parts by weight of sulfuric acid, the feed rate being adjusted to maintain a substantially constant liquid level in the fume-off chamber 10. During the fume-off operation the temperature of the liquid in the fume-off pot 10 is maintained as closely as possible at about 106° C. The evolved gases and vapors pass upwardly through the conduit 25 into a condenser 26, any condensate being returned to the fume-off pot through the trapped line 27; uncondensed vapors and gases pass through the vapor outline 29 to the fume stack (not shown).

The fumed-off reaction mixture overflows through the hydraulic legs 22 and 23 into the upper boiling tube 11. The boiling tubes consist of a number of steam jacketed horizontal tubes disposed above one another and so connected as to form a continuous flow path. Each of the horizontal tubes is provided with suitable dams 28 so that each horizontal tube is maintained partially full of liquid. The fumed-off mother liquor flows into one end of the upper tube and thence in sequence through the lower horizontal boiling tubes. The lowermost boiling tube is provided with a take-off tap 30 through which residual sulfuric acid-acetic acid may be withdrawn. The temperature of the liquid in the uppermost boiling tube is maintained at about 125° C. while that of the lowermost boiling tube is held at about 140° C.

In order to minimize back pressure effects, a vapor line 31 connects the vapor space of the horizontal boiling tubes to the sulfuric acid entrainment separator 12.

As the vapors from the boiling tubes ascend through the entrainment separator 12 (which is preferably packed with Raschig rings or other suitable surface material) the entrained sulfuric acid or other liquid in the vapors is separated, the vapors ascending to the condenser 13. The condensed acetic acid thence flows into the recovered acetic acid storage tank 32.

Inasmuch as the residual acid flowing from the lowermost boiling tube may contain 60% acetic acid or more, it is preferable to recirculate this acid to the fume-off vessel, this being accomplished by the return line 33 which connects with the recycle storage tank 34. The residual acid in the storage tank 34 is forced by the pump 35 through the return line 36 to the overhead

storage tank 37 whence it flows through the valved line 38 to the fume-off pot 10.

The boiling tubes 11 are preferably steam-jacketed (not shown) in order to supply heat to the liquid undergoing distillation.

By way of recapitulation, in using the apparatus described with reference to Fig. 1, assuming that the process is to be used in connection with the manufacture of "anhydride cyclonite," the cycle of operations is preferably as follows:

(1) Treat the undiluted reaction mixture (consisting of a slurry of cyclonite in the undiluted reaction liquor) with anhydrous ammonia until nearly all of the nitric acid has been neutralized, leaving approximately 0.5% of the nitric acid un-neutralized. The resulting slurry will then consist of cyclonite, acetic acid, ammonium nitrate, about 0.5% unneutralized nitric acid, and other reaction products, impurities, etc.

(2) Filter the cyclonite and other solid products.

(3) Mix the filtrate with sulfuric acid, forming a solution preferably containing about 9 to 10% sulfuric acid in starting up the acid recovery system, the filtrate and the sulfuric acid entering the fume-off vessel preferably being prewarmed to about 50° C.

(4) Heat the liquid in the hydraulic leg 22 until fume-off is initiated and thereafter maintain the temperature of the liquid in the fume-off pot at about 106° C.

(5) After the fume-off has started, continue charging to the fume-off vessel 10, prewarmed (50° C.) crude acid and sulfuric acid in the proportions of about 95% by weight crude acetic acid and 5% by weight sulfuric acid.

(6) Permit the fumed-off liquor to flow into the boiling tube evaporator, maintaining the temperature in the uppermost tubes of the evaporator at a temperature slightly above the boiling point of acetic acid (for example at 120° C.) and the lowermost tubes of the evaporator at a temperature not exceeding about 140° C.

(7) Condense the acetic acid vapors passing through the entrainment separator 12, in the condenser 13.

(8) Continually withdraw residual acid (about 40% sulfuric, 60% acetic acid) from the tap-off line 30, recycling either all or a portion thereof where desired to the fume-off vessel 10.

It will be apparent to those skilled in the art that many variations may be made in the foregoing detailed procedure without departing from the spirit and scope of the invention. We therefore intend to be limited only in accordance with the following patent claims.

We claim:

1. A method of recovering acetic acid from mixtures containing ammonium nitrate, nitric acid, acetic acid and residual nitramine explosives, which comprises heating the reaction mixtures in the presence of sulphuric acid to effect fume-off, and thereafter distilling the fumed-off reaction mixture from a residual acid containing about 15 to about 40% sulfuric acid.

2. A method of recovering acetic acid from mixtures containing ammonium nitrate, nitric acid, acetic acid and residual nitramine explosives, which comprises heating the reaction mixture at a temperature from about 100 to about 112° C. in the presence of sufficient sulfuric acid to effect fume-off, and thereafter distilling the fumed-off reaction mixture from a residual acid comprising about 15 to about 40% sulfuric acid and about 60 to about 85% acetic acid, said re-

sidual acid being maintained at a temperature of about 120 to about 140° C.

3. The method of claim 2 wherein said sulfuric acid is present to the extent of about 5% to about 10% by weight.

4. The method of claim 2 wherein said fumed-off reaction mixture is distilled from a mixture of sulfuric acid and acetic acid of about 35 to about 40% sulfuric acid strength.

5. In the recovery of acetic acid from residual reactions mixture liquors obtained in the manufacture of nitramine explosives, the method of working up the reaction mixture which comprises treating the undiluted reaction product with anhydrous ammonia to reduce the nitric acid content thereof to below about 1%, separating the solid reaction products from the mother liquor, heating the mother liquor from which the solid has been removed to a temperature between about 95 to about 112° C. in the presence of sufficient sulfuric acid to effect a fume-off, distilling the fumed-off mother liquor from a residual acid comprising about 15 to about 40% sulfuric acid and about 85% to about 60% acetic acid, maintained at about 120 to about 140° C., and condensing the acetic acid distilled from said mixture.

6. The method of claim 5 wherein the separated solid reaction products are treated with hot water to leach out the water soluble and water hydrolyzable impurities therein, whereby to recover cyclonite.

7. The method of claim 5 wherein said sulfuric acid is present to the extent of about 5 to about 10% by weight.

8. The method of claim 5 wherein said residual acid is utilized in the fume-off of further quantities of said crude acid.

9. A method of recovering acetic acid from a crude acid containing ammonium nitrate, nitric acid, acetic acid, and a nitramine explosive, which comprises mixing said crude acid with sulfuric acid to form a mixture containing about 5 to

about 10% sulfuric acid, heating said mixture at a temperature of about 100-112° C. to effect a fume-off of said mixture withdrawing a portion of the fumed-off mixture and distilling the same from a residual acetic acid-sulfuric acid mixture having a boiling point between about 115 and about 140° C.

10. A method for the recovery of acetic acid from residual reaction liquor obtained in the manufacture of cyclonite, which comprises: treating the undiluted reaction mixture with sufficient anhydrous ammonia to reduce the nitric acid content thereof to below 1% by weight, separating the solid reaction products including solid cyclonite from the reaction mixture; heating the mother liquor remaining after separation of said cyclonite in the presence of about 5% to about 10% by weight sulfuric acid, at a temperature sufficient to produce a fume-off, whereby to destroy the ammonium nitrate and nitric acid content of said mother liquor; distilling the acetic acid from the fumed-off mother liquor from a body of about 15 to about 40% sulfuric acid and about 85% to about 60% acetic acid, maintained at a temperature of about 120° C. to about 140° C., whereby to destroy any residual cyclonite contained in said mother liquor, condensing the acetic acid distilled from said mixture; and mixing the residual undistilled sulfuric acid-acetic acid mixture with further quantities of said mother liquor prior to fume-off and distillation thereof.
